UNITED STATES PATENT OFFICE.

DAVID S. NASH, OF CORSICANA, AND JAMES E. LETT, JR., OF DALLAS, TEXAS.

ROAD LOG AND MAP DISPLAY DEVICE.

Application filed April 2, 1925. Serial No. 20,201.

To all whom it may concern:

Be it known that we, DAVID S. NASH and JAMES E. LETT, Jr., citizens of the United States of America, residing at Corsicana, 5 Navarro County, Texas, and in Dallas, in the county of Dallas and State of Texas, respectively, have invented certain new and useful Improvements in Road Log and Map Display Devices, of which the following is 10 a specification.

This invention relates to new and useful improvements in road log and map display devices. The object of the invention is to co-ordinate a road log with a road map in 15 a new and novel manner.

A further object is to provide means for exhibiting a road log so as to give the route in either direction between two given places.

20 Another object is to provide a device of the character described which may be installed at the road side or other point of information and provided with a display panel on which any desired matter may be 25 exhibited.

A construction designed to carry out the invention will be hereinafter described together with other features of the invention.

The invention will be more readily understood from a reading of the following 30 specification and by reference to the accompanying drawings, in which examples of the invention are shown, and wherein:

Fig. 1 is a front elevation of a device 35 constructed in accordance with our invention,

Fig. 2 is a side elevation of the same,

Fig. 3 is a vertical sectional view on the line 3—3 of Fig. 1,

40 Fig. 4 is an enlarged cross-section taken on the line 4—4 of Fig. 1,

Fig. 5 is a front elevation of an alternate form in which the invention may be carried out,

45 Fig. 6 is a side elevation of the same,

Fig. 7 is a vertical sectional view on the line 7—7 of Fig. 5, and

50 Fig. 8 is an enlarged cross-section taken on the line 8—8 of Fig. 5.

In the drawings the numeral 10 designates a vertical cabinet having side walls 11, and a rear wall 12 with a false rear wall 13. The front edges of the side walls are connected by a cross brace bar 14. A cylindrical housing 15 is supported at its ends in semi-circular seats 16 cut in the upper ends of the

side walls in front of the false wall 13. This housing has a longitudinal slot or opening 17 in its front side above its horizontal axis; whereby portions of the surfaces of drums 60 18 and 19, respectively, mounted on opposite sides of a partition 20 in the housing, may be observed.

Each drum has an axial trunnion 21 at its inner end and these trunnions are journaled 65 in circular bearing races or sumps 22 in opposite sides of the partition 20. The outer end of each drum is mounted on a stub shaft 23 journaled in the end of the housing and having a crank handle 24. The 70 drums may be made solid or hollow.

On the surface of each drum is printed or otherwise applied in any suitable manner, a road log. On the drum 18 the road is 75 logged in one direction between two cities and on the drum 19 the same road is logged in the opposite direction between the same cities. For instance on the drum 18 the road from Dallas to Houston, Texas, may be displayed; while on the drum 19, the return 80 road from Houston to Dallas may be shown, but this is not essential as two different routes may be logged on the drums. Either drum may be revolved independently of the other by means of its crank handle 24. 85

Each trunnion 21 has a circumferential groove 25 for receiving a cord 26 which is wound therein when the drum is revolved. Each end of the cord is fastened to one of the trunnions and said cord passes through 90 apertures 27 in the false walls 13 which extends above the walls 11. The cord is looped around a pulley 28 at the center of the bottom of a map slide or board 29. The looped portion depends from pulleys 30 mounted 95 in the space between the wall 13 and said slide, below a cap 31 closing the upper end of said space.

It will be seen that when either drum is 100 revolved to wind the cord 26 thereon, the slide 29 will be raised. On the face of the slide may be displayed map (not shown) on which the routes logged on the drum may be shown with adjacent towns and any other desired information. A display panel 32 105 may be fastened to the rear side of the wall 12 so as to extend above the top of the cabinet and advertising and other data may be displayed thereon. Any suitable means for guiding the slide 29 may be employed. 110

In Figs. 5 to 8 we have illustrated an alternate form of the invention in which the

only difference resides in the construction of the drums and the cord connection for raising the map slide, otherwise the parts are the same. In this form the drums 18' 5 and 19' are made integral and the central partition 20 is eliminated. The drums are separated by a central circumferential groove 33 in which one end of a cord 34 is fastened. This cord passes through an aperture 27' in the false wall 13, over a pulley 30' and has its depending end fastened by a screw or the like 35 to the lower end of the slide 29. While both drums will be revolved at the same time, the user may observe either or both.

Various changes in the size and shape or the different parts, as well as modifications and alterations may be made within the scope of the appended claims.

20 What we claim, is:

1. In a road log and map display device, a cabinet, a housing carried by the cabinet, a drum in the housing having a road log on its surface, means for revolving the drum, a vertically movable map slide normally concealed in the cabinet, and means actuated by the drum for raising the slide out of the cabinet when the drum is revolved.

2. In a road log and map display device, 30 a cabinet, a housing carried by the cabinet, a drum in the housing having a road log on its surface, means for revolving the drum, a vertical movable map slide normally concealed in the cabinet, and a flexible connection between the drum and the slide wound when the drum is revolved, whereby the slide is elevated.

3. In a road log and map display device, 40 a cabinet, a housing carried by the cabinet, drums mounted to revolve in the housing and having road logs displayed on their surfaces, crank handles for revolving said drums, a movable map slide mounted in the cabinet, and means actuated by the drum for elevating said slide when said drums are revolved.

4. In a road log and map display device, 50 a cabinet, a housing carried by the cabinet, drums mounted to revolve in the housing and having road logs displayed on their surfaces, crank handles for revolving said drums, a movable map slide mounted in the cabinet, and a flexible connection between the drums and the slide for elevating said slide when the drums are revolved.

5. In a road log and map display device, a cabinet, a housing carried by the cabinet, drums mounted to revolve in the housing and having road logs displayed on their surfaces, crank handles for revolving said drums, a movable map slide mounted in the cabinet, a flexible connection between the drums and the slide for elevating said slide when the drums are revolved, and a display panel extending above the cabinet in 60 rear of the slide.

6. In a road log and map display device, a cabinet, a drum mounted to revolve on the cabinet and having a road log on its surface, a vertically movable map slide normally concealed in the cabinet in rear of the drum, and means actuated by the drum for elevating the slide when the drum is revolved.

7. In a road log and map display device, 75 a cabinet, a drum mounted to revolve on the cabinet and having a road log on its surface, a vertically movable map slide normally concealed in the cabinet in rear of the drum, means actuated by the drum for elevating the slide when the drum is revolved; a display panel extending upwardly from the cabinet in rear of the slide.

8. In a road log and map display device, 85 a cabinet, a cylindrical housing having a display opening mounted on said cabinet, road-log drums mounted in said housing, means for revolving said drums, a map slide mounted in said cabinet, a flexible connection extending between said slide and the drums, and a pulley over which the connection passes, the slide being normally lowered into the cabinet.

9. In a road log and map display device, 95 a cabinet, a cylindrical housing having a display opening mounted on said cabinet, road-log drums mounted in said housing, means for revolving said drums, a map slide mounted in said cabinet, a flexible connection extending between said slide and the drums, a pulley over which the connection passes, the slide being normally lowered into the cabinet, and a display panel secured to the cabinet and extending above the same in rear of the slide.

105 In testimony whereof we affix our signatures.

DAVID S. NASH,
JAMES E. LETT, JR.
